Primary Examiner — Bao-Yen T Nguyen*Assistant Examiner* — Bethany Louise Mallino(74) *Attorney, Agent, or Firm* — Kunzler Bean & Adamson, PC; Bryan W. Pitt(57) **CLAIM**

The ornamental design for a hat hanger, as shown and described.

DESCRIPTION

FIG. 1 is a top, front, right side perspective view of a hat hanger, showing my new design;

FIG. 2 is a top, front, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion framed “9” in FIG. 1;

FIG. 10 is another enlarged view of the portion framed “10” in FIG. 2; and,

FIG. 11 is an perspective view showing the hat hanger in half folded state.

The dot-dash broken line rectangular frames in FIGS. 1-2 and 9-10 define the boundary of an enlarged view and form no part of the claimed design.

1 Claim, 11 Drawing Sheets(56)
